UNITED STATES PATENT OFFICE.

MARTIN M. JOHNSON, OF DAYTON, OHIO.

GAME-TABLE.

No. 828,211.

Specification of Letters Patent.

Patented Aug. 7, 1906.

Application filed August 19, 1905. Serial No. 274,864.

To all whom it may concern:

Be it known that I, MARTIN M. JOHNSON, a citizen of the United States, residing at Dayton, in the county of Montgomery and State 5 of Ohio, have invented certain new and useful Improvements in Game-Tables, of which the following is a specification.

My invention relates to game-tables, and especially to that class of game-tables where- 10 on a game is played with balls impelled by cues or like devices.

The object of my invention is to provide a game-table for the playing of a game requiring a great degree of skill and precision.

15 It is a further object of my invention to provide a game-table the buffers of which are adapted to be accurately adjusted with reference to each other, so that a perfect alignment of the buffers may be obtained.

20 With these and other objects in view the present invention consists in the combination and arrangement of parts, as will be hereinafter more fully described, shown in the accompanying drawings, and particularly pointed 25 out in the appended claims, it being understood that changes in the form, proportion, size, and minor details may be made within the scope of the claims without departing from the spirit or sacrificing any of the ad- 30 vantages of the invention.

In the drawings, Figure 1 is a top plan view of my improved game-table. Fig. 2 is a vertical sectional view of my improved game-table, taken on line 2 2 of Fig. 1. Fig. 3 is a 35 detail vertical sectional view of one of the buffers.

Like characters of reference designate corresponding parts throughout the several views.

40 In its essential features my invention comprises a table having a plane surface, preferably square in form, and having suitable cushions arranged along each of its sides, as indicated at 1. The cushions 1 are made sec- 45 tional, and between the several sections are provided pocket-openings.

In its preferred proportion my game-table is provided upon each of its sides with five 50 pocket-openings, though it is obvious that any other number may be as well used, and in each of said pocket-openings is provided an aperture 4 through the table-surface, beneath each of which is suspended a bag-like pocket 4, preferably of fabric. The several 55 sections forming the cushions along the sides

of the table are covered with fabrics of different colors, so that the cushion along each side of the table differs in color from the other cushions, as indicated by the shading in Fig. 1. 60

Upon the surface of the table are arranged a plurality of circular resilient buffers up- 65 standing from the table-surface and of a height approximately equaling the height of the side cushions. The circular buffers (in- 70 dicated at 5) are preferably knob shape in form and constructed of a base 6, a cushion 7, and a screw-threaded cap 8. The base and cushion are provided with a circular passage for the reception of a vertical pin 9, secured to 75 the table. The upper end of said pin is screw-threaded to receive cap 8, said cap oper- 80 ating to hold the base and cushion firmly in position. The buffers are so disposed upon the surface of the table as to form a ball- 85 passage way extending from each pocket- 90 opening directly opposite, as indicated at 10, and obliquely, as indicated at 11. The cushion 7 is of greater diameter than the base and cap, thereby preventing the balls from being marred when they come in contact with the buffer and causing the necessary rebound to 95 said balls. The construction of the buffer is such that by tightening the cap 8 the rubber will be caused to spread. In this way the 100 distance between adjacent buffers can be regulated and straight ball-passage ways se- 105 cured. The buffers are preferably colored to correspond with the cushions, the buffers in each triangular section formed by the dia- 110 gonals of the table being of the same color as the side of the table forming the third side of said triangle.

The table is provided with any approved form of frame to hold the cushions and set 95 upon any convenient support, as legs 12. A plurality of balls are provided, equal in num- 100 ber to the number of pockets and are colored to correspond with the colors of the cushions, five being of the same color as one cushion, five being of the same color as another, and so on. For playing the balls are designed to be arranged as indicated in Fig. 1, each 105 player having five balls. The balls B, C, D, E, and F are designed to be pocketed in a cer- 110 tain order or otherwise in correspondingly- designated pockets opposite which they are placed. Ball F, used as the cue-ball, is pocketed in its designated pocket after the other balls are in their respective pockets.

Having thus described my invention, what I claim as novel, and desire to secure by Letters Patent, is—

1. In a game-table upon which balls are to be impelled, suitable cushions arranged and differently colored along each of its sides and provided with a plurality of pocket-openings therethrough, a pocket disposed beneath each of said openings, circular knob-like buffers arranged upon said table to form passage-ways, said passage-ways being arranged to register with the pocket-openings and means for varying the diameter of said buffers at will.
- 15 2. In a game-table, a circular buffer comprising a stem adapted to be secured to the table, a base, provided with a vertical opening therethrough, adapted to rest upon the face of the table, a cushion of greater diameter than said base, provided with a similar opening located on said base, and a cap adapt-

ed to be secured to the upper end of said stem to hold said base and cushion in position.

3. A game-table upon which balls are to be impelled, having a plurality of buffers arranged upon its surface and means for varying the diameter of said buffers at will. 25

4. A game-table, upon which balls are to be impelled, having a series of ballways formed by a plurality of circular buffers arranged upon the surface of said table, said buffers being formed of compressible material, and means for compressing said buffers, whereby their diameter may be varied at will and maintain the alinement of the ball- 30 ways. 35

In testimony whereof I affix my signature in presence of two witnesses:

MARTIN M. JOHNSON.
